UNITED STATES PATENT OFFICE.

JOHN W. COSGROVE, OF MEDFORD, MASSACHUSETTS, ASSIGNOR TO UNITED SHOE MACHINERY CORPORATION, OF PATERSON, NEW JERSEY, A CORPORATION OF NEW JERSEY.

APPLYING APPARATUS.

Application filed March 4, 1920. Serial No. 363,297.

To all whom it may concern:

Be it known that I, JOHN W. COSGROVE, a citizen of the United States, residing at Medford, in the county of Middlesex and 5 State of Massachusetts, have invented certain Improvements in Applying Apparatus, of which the following description, in connection with the accompanying drawings, is a specification, like reference characters on 10 the drawings indicating like parts in the several figures.

My invention relates to apparatus for applying to various materials such substances as liquids, an instance of this class 15 of apparatus being found in those employed for wetting soles of shoes prior to their channeling and the turning of the channel flaps. In this wetting apparatus it is desirable that the water or other liquid shall 20 thoroughly penetrate the soles. This, however, is a matter of much difficulty, since modern tanning processes make the leather of which the soles are formed repellent of moisture, and also because of the presence 25 of such material as chalk upon the surfaces, which tends to prevent the absorption of the liquid. Objects of this invention are to provide a simple and easily operated apparatus, by which soles and the like may be effectively treated over unbroken surfaces, as by 30 having applied to them a liquid which is caused to enter their pores.

In the accomplishment of these objects, as a feature of my invention, I combine with 35 means for advancing the work to be operated upon, an applying member having a surface arranged to roughen the surface of the work and movable in its contact with said work in a direction opposite to the advance. 40 This causes the surface under treatment to be wiped clean by the applying member, and the fibers of the material to be separated or displaced to increase the absorptive effect. Preferably, the applying member consists 45 of a roll operating in a receptacle containing the substance with which the work is to be treated, this roll having projecting portions contacting with the work and so rotating with respect to the advance of said 50 work that it travels in the opposite direction at its points of contact therewith. This not only produces the cleaning and loosening effect previously mentioned, but also brings up from the receptacle and holds in 55 front of the work after it has been rubbed

by the applying surface, a body of the substance to be applied, which is thus enabled to enter the work thoroughly.

To increase the rate at which the apparatus operates upon the work, I may so arrange it that it simultaneously acts upon a plurality of pieces, and, in this connection, a further feature of the invention lies in plural means situated on one side of the applying member, each means comprising co-operating advancing surfaces and each means acting independently of the associated means for independently effecting the feed of the pieces. In the present embodiment of the invention, the roll or other applying member is so elongated that plural work pieces may be acted upon at one time, and along this applying roll are plural feeding members, which will exert their influence independently. They are preferably in the form of pressure-rolls, mounted for independent movement, and are thus adapted to act properly at the same time upon work of different thicknesses. Since it is desirable to maintain a positive advance 70 of the work during the entire time which the applying member acts upon it, I have provided feeding means at each side of the applying member, the forward of which causes the movement of the work after it has passed out of engagement with the rear feeding means. To bring about the independent control of the separate work pieces just discussed, the feeding means consists of opposite series of rolls arranged in aligned 75 pairs.

The applying member of this invention is shown as in the form of a roll having depressions to convey to the work the substance to be applied and to rub this in by the differential movement. To prevent the dividing walls between the depressions from interfering with the application, as by causing, through continuous contact with the same portion of the work, dry 80 areas thereon, another feature of the invention consists in arranging the adjacent depressions, considered circumferentially of the roll, between different transverse planes. The dividing walls will consequently not be aligned, and the area shielded from the wetting effect by the walls of one depression will be acted upon by a succeeding depression. Moreover, the 85 surface of the work will be continuously 90

roughened by the action of the walls. In the preferred form of the apparatus, the depressions are arranged helically about the applying roll, being, in the organization illustrated, furnished by a helical rib with intersecting longitudinal ribs.

The accompanying drawings show a particular embodiment of the invention adapted for the wetting of soles,

10 Fig. 1 being an end elevation of the apparatus;

Fig. 2, a vertical section on the line 2—2 of Fig. 1;

15 Fig. 3, an enlarged horizontal section on the line 3—3 of Fig. 1; and

Fig. 4, an enlarged sectional detail, illustrating the co-operation of the work with the applying roll and the substance which it delivers.

20 Upon a suitable standard 10 is supported a base frame 12, from the rear of which project horizontal arms 14, 14, carrying a work-receiving table 16. Just in front of this table, the frame 12 has fixed upon it a tank 25 or receptacle 18 for water or other substance to be applied, this tank having an inclined bottom wall 20 leading downwardly from the forward extremity of the tank to the rear, and having near the latter side a drain-pipe 22, controlled by a cock 24. Through this pipe the liquid, with the accumulated waste and foreign matter from the work, may be removed when desired. To maintain a constant level of liquid in the tank, I prefer to supply it from an elevated reservoir 26, carried upon an arm 28 projecting from the side of the frame 12, and curved over the tank. From the bottom of this reservoir leads a pipe 30, the lower end of which terminates at the level in the tank at which it is desired to keep the surface of the contained liquid. The reservoir and this connecting pipe are arranged to provide a barometric feed, flow occurring only when 35 and as soon as the height of the liquid in the tank falls below the delivering extremity of the pipe 30. The reservoir may be filled through a pipe 32 entering its side, this pipe being normally closed by a cock 34. To allow the liquid to be introduced, the reservoir may be vented at the top through an air-cock 36. At the time of emptying the tank 20, flow through the pipe 30 may be stopped by closing a cock 38 40 therein. This is also shut during the filling of the reservoir.

In the side walls of the tank 20 is journaled an applying roll 40, the upper peripheral portion of which projects above the top 45 of the tank, while the roll, generally, is so related to the end of the pipe 30 that a considerable portion is immersed in the contained liquid. This roll 40 is rotated at the desired speed by a belt 42, connecting 50 stepped pulleys 44 and 46 upon the roll

shaft and a driving shaft 48, respectively. The driving shaft is mounted to turn in a bracket 49 bolted to the side of the base frame, and is rotated by a belt 50, joining a source of power to fast and loose pulleys 52 upon the driving shaft. To enable the applying roll 40 to effectively bring up from the tank 20 the contained liquid and apply it to the work, said roll is formed with closely placed pockets or depressions 54, these, in the present instance, lying between side walls 56, 56, which extend in a generally circumferential direction about the roll, and end walls 58, 58 connecting the side walls and lying longitudinally of the roll surface. If these conveying depressions exactly tracked in the rotation of the roll, there would be constant lines of separation produced by the end walls 58 between the circumferential series of depressions, which would tend to remain dry and thus impair the wetting action of the machine. To avoid this, the adjacent depressions of the series lie between different planes intersecting the roll transversely. Preferably, they are arranged helically, the rib forming the walls 56 being furnished by a continuous helix. As a convenient manner of constructing the depressions thus arranged, this helical wall may be integral with the body of the roll, while the walls 58 consist of ribs or bars set in slots cut through the convolutions of the helix. As a result of this, there is a progressive lateral displacement of the circumferential depressions, and similarly of their end walls 58, so that an area, which may be left dry under the walls when one depression passes over the work, will be moistened by a succeeding depression which is out of alignment with those preceding it.

The work is fed across the upper surface of the applying roll, preferably at a rather slow speed as compared with the rotation of the roll and in a direction opposite to such rotation, by a roll 60 journaled in the tank walls parallel to the applying roll, and driven oppositely thereto by a chain of gearing 62 connecting the feed-roll 60 with the driving shaft 48. The feed-roll is shown as grooved longitudinally to give better engagement for advancing the work, and to render it effective in its feeding action, there co-operates with it a pressure means mounted near the top of the tank. I have shown this pressure means as consisting of rolls 64, each of which is of such length that it will contact across the entire width of the largest sole to be fed. The pressure-rolls are yieldably mounted, in a manner now to be described, and, because of their independence, permit the application of the correct feeding pressure to all the work simultaneously acted upon by the applying roll, regardless of the thickness of the pieces. Extending across the top of the

tank above the applying roll is a rod or like supporting bar 66, fixed in brackets or extensions 68, 68 from the side walls of the tanks. Uniformly spaced along this rod are blocks 70, each of which appears as divided at one side and clamped in place upon the rod by a screw 72, drawing the parts toward one another. Each block has rearwardly and downwardly extending arms 74, 74, upon which is pivoted at 76 a carrier 78 for one of the rolls 64. Projecting upwardly from each block, and being, as illustrated, formed integrally therewith, is a casing 80 containing a spring 82, which, exerting its force upon the pivoted carrier, presses the corresponding feed-roll 64 toward the feed-roll 60. Threaded through the upper extremity of each casing is a screw 84, by which different degrees of compression may be applied to the spring 82, and thus the force with which the work is engaged between the feed-rolls varied. To limit the downward movement of each upper feed-roll, and thus hold it normally out of contact with the lower, a screw 86 is threaded through a portion of the carrier 78, contacting with the wall of the casing 80. Changes may be made in the position of this screw to alter the separation between the rolls. I prefer to so locate these feed-rolls 60 and 64 that their bite is somewhat below the applying surface of the roll 40, causing them to hold the work with some force against said surface. To increase this action, and also to give a greater area of contact between the work and the applying roll, spring fingers 88 are located above the roll, these preferably being curved so that their contour is generally similar to that of the adjacent portion of the roll periphery, thereby increasing the length of the sole which is held under treatment upon the applying roll. As shown herein, these fingers 88 are divided from a plate 90 of spring metal, this plate being fixed at the lower extremities of arms 92, which are respectively secured at 94 to the rod 66. The position of the arms 92 may be maintained by set screws 95, and by loosening these the angular relation of the arms to the rod, and therefore of the fingers 88 to the roll, may be changed to vary the pressure of said fingers upon the work.

The feeding action of the rolls 60 and 64 is continued by similar lower and upper rolls 96 and 98, respectively, lying at the opposite side of the applying roll from the rolls first mentioned, and at a somewhat higher level to bring the work passing through them clear of the top of the tank. The lower roll 96 is journaled in the tank walls, is continuous throughout its length and grooved to better engage the work similarly to the roll 60, and is driven by a belt

100 engaging pulleys 102 and 104, respectively, secured upon the shafts of the rolls 60 and 96. The upper rolls 98 are divided, as are the rolls 64, each section being mounted upon a carrier arm 106, bifurcated and turning about the rod 66 at the opposite sides of a block 70. Situated between each carrier arm 106 and an arm 108 projecting upwardly from the associated block, is a spring 110, surrounding a bolt 112, which passes through openings in the arms. This spring applies to its roll 98 the feeding pressure, the extent of downward movement under the influence of the spring being limited by a nut 114 upon one end of the bolt. The effective spring tension may be altered by the substitution of springs of different lengths.

I have found that the work more effectively absorbs the liquid if this be heated, and to this end there is shown, projecting inwardly from an end wall of the tank, a cylindrical casing 116, within which is contained a source of heat, as an electric unit 118. To this unit current may be supplied through conductors 120. The casing, being entirely surrounded by the liquid, transmits the heat of the contained unit practically without loss, and the whole body in the tank is warmed to a temperature which produces its most ready absorption by the work.

In using the apparatus for the tempering of shoe soles, the operator takes them from a stock supported upon the table 16, and advances them over a cover-plate 122 extending across the rear of the tank 20 so that they enter between the feed-rolls 60 and 64 at all the feeding sections. I have shown upon this cover vertical partitions 124, dividing it into sections corresponding in number to the rolls 64, this arrangement insuring the proper presentation of the work to the feeding sections. Upon engagement by the feed rolls, the work is advanced across the top of the applying roll beneath the fingers 88, which bend it down into contact with the applying surface. This, traveling toward the feed-rolls in the opposite direction to the advance of the work pieces, drags the walls separating the roll-depressions across the surfaces to be treated, scraping off foreign substances and roughening the fibers of the material. As a result, the pores of the material are freed and opened, so that the liquid in the depressions readily enters the work. Then, as each sole passes beyond the contacting surface of the applying roll, it comes under the influence of the body of liquid appearing at L in Fig. 4 of the drawings, which has been raised from the tank in excess of that which is carried beneath the work by the roll depressions, and absorbs an additional quantity therefrom, the sole surfaces, by their roughening and preliminary

wetting, being prepared to readily take this up. As the rear end of each sole leaves the feed-rolls 60 and 64, the forward end is seized by the rolls 96 and 98, and the advance 5 maintained. The forward feed-rolls finally discharge the treated soles upon a shelf 126 secured at the forward and upper edge of the tank.

Having described my invention, what I 10 claim as new and desire to secure by Letters Patent of the United States is:

1. In an applying apparatus, means for advancing the work, and an applying member 15 movable in contact with the work in a direction opposite to its advance, said applying member being provided with a surface formed and arranged to roughen the oppositely moving face of the work.

2. In an applying apparatus, means for 20 advancing the work, and a rotatable applying roll having projecting portions contacting with the work and moving at the points of contact in the opposite direction to the advance.

3. In an applying apparatus, a receptacle 25 for the substance to be applied, an applying roll rotatable in the receptacle, pairs of feeding rolls situated at opposite sides of the applying roll, each pair of rolls being arranged 30 to successively move the work over the applying roll in a direction opposite to the travel of that portion of the applying roll contacting with said work and to positively hold it to receive the rubbing action of said 35 applying roll.

4. In an applying apparatus, means for advancing the work, an applying member 40 movable in contact with the work in a direction opposite to its advance, and means extending about and corresponding in contour to the applying member for forcing the work into engagement with said applying member.

5. In an applying apparatus, means for 45 advancing the work, a rotatable applying roll contacting with the work and moving at the points of contact in the opposite direction to the advance, and a spring member co-operating with the work opposite the roll 50 and having a portion substantially concentric to said roll.

6. In an applying apparatus, a receptacle 55 for the substance to be applied, an applying roll rotatable in the receptacle, feeding rolls situated at opposite sides of the applying roll and arranged successively to move the work over the applying roll, and a plurality of spring fingers contacting with the work 60 opposite the applying roll and between the feeding rolls, each of the fingers having a portion substantially concentric to said applying roll.

7. In an applying apparatus, an applying 65 member arranged to operate simultaneously upon a plurality of separate objects through-

out its length, and plural means situated on one side of the applying member, each means comprising co-operating advancing surfaces and each means acting independently of the associated means for effecting the feed of 70 such separate objects.

8. In an applying apparatus, an elongated rotatable applying roll arranged to operate simultaneously upon plural pieces of work, a plurality of feeding rolls situated at different points along the applying roll, and a driven roll co-operating with the feeding rolls in the advance of the work-pieces. 75

9. In an applying apparatus, an elongated rotatable applying roll arranged to operate simultaneously upon plural pieces of work, a driven feeding roll extending along the applying roll, and a plurality of independently rotatable rolls arranged in a series 80 along the driven roll. 85

10. In an applying apparatus, an elongated rotatable applying roll arranged to operate simultaneously upon plural pieces of work, a driven feeding roll extending along the applying roll, and a plurality of pressure-rolls co-operating with the driven roll and being independently yieldable. 90

11. In an applying apparatus, an applying member arranged to operate simultaneously upon a plurality of separate objects throughout its length, and means acting independently upon such separate objects at each side of the applying member to effect 95 their feed.

12. In an applying apparatus, an elongated rotatable applying roll arranged to operate simultaneously upon plural pieces of work, and a plurality of feeding rolls extending in plural series longitudinally of the applying roll and at opposite sides thereof, said opposite feeding rolls being arranged in aligned pairs. 100 105

13. In an applying apparatus, an elongated rotatable applying roll arranged to operate simultaneously upon plural pieces of work, a driven feeding roll extending along the applying roll and being rotatable in a direction opposite thereto, and a plurality of independently rotatable rolls arranged in a series along the driven roll. 110 115

14. In an applying apparatus, a receptacle, an applying member operating in the receptacle and over which the work is advanced, a support extending across the receptacle adjacent to the applying member, and members mounted upon the support for movement independently of one another and for engagement with the work at different points in its advance. 120

15. In an applying apparatus, a receptacle, an applying member operating in the receptacle and over which the work is advanced, a support extending across the receptacle adjacent to the applying member, and members movably mounted upon the 125 130

- support for engagement with the work at different points in its advance.
16. In an applying apparatus, a receptacle, an applying roll operating in the receptacle and over which the work is advanced, a support extending across the receptacle adjacent to the applying roll, and pressure-rolls yieldably mounted upon the support and arranged to engage the work at opposite sides of the applying roll. 50
17. In an applying apparatus, a receptacle, an applying roll operating in the receptacle and over which the work is advanced, a support extending across the receptacle adjacent to the applying roll, pressure-rolls yieldably mounted upon the support and arranged to engage the work at opposite sides of the applying roll, and pressure-fingers carried by the support and co-operating with the applying roll between the pressure-rolls. 60
18. In an applying apparatus, a tank, an applying roll rotatable therein, a rod extending across the tank above the applying roll, arms pivotally mounted upon the rod and terminating at opposite sides of the applying roll, and pressure-rolls mounted upon the arms. 65
19. In an applying apparatus, a tank, an applying roll rotatable therein, a rod extending across the tank above the applying roll, arms pivotally mounted upon the rod and terminating at opposite sides of the applying roll, springs mounted upon the rod and acting upon the arms, and pressure-rolls mounted upon the arms. 70
20. In an applying apparatus, a tank, an applying roll rotatable therein, a rod extending across the tank above the applying roll, series of arms pivotally mounted upon the rod and terminating at opposite sides of the applying roll, and a series of pressure-rolls carried by the arms at each side of the applying roll. 75
21. In an applying apparatus, a tank, an applying roll rotatable therein, a rod extending across the tank above the applying roll, arms pivotally mounted upon the rod and terminating at opposite sides of the applying roll, pressure-rolls mounted upon the arms fixed to the rod between the pivoted arms, and spring-fingers secured to the fixed arms and co-operating with the applying roll. 80
22. In an applying apparatus, a tank, an applying roll rotatable therein, a rod extending across the tank above the applying roll, blocks fixed upon the rod, arms pivoted upon the rod adjacent to the blocks, arms pivoted upon the blocks, springs interposed between the blocks and both sets of arms, and pressure-rolls rotatable upon the arms. 85
23. In an applying apparatus, a tank, an applying roll rotatable therein, a rod extending across the tank above the applying roll, blocks fixed upon the rod, arms pivoted upon the rod adjacent to the blocks, arms pivoted upon the blocks, springs interposed between the blocks and both sets of arms, means carried by the arms and arranged to vary the tension of the springs, and pressure-rolls rotatable upon the arms. 90
24. In an applying apparatus, an applying roll having retaining depressions for the substance to be applied, adjacent depressions circumferentially of the roll being arranged between different transverse planes, and means arranged to cause the substance in the depressions to be rubbed over the surface of the work. 95
25. In an applying apparatus, an applying roll having helically arranged depressions for retaining the substance to be applied, and means arranged to cause the substance in the depressions to be rubbed in a continuous coating over the surface of the work. 100
26. In an applying apparatus, an applying roll having about its periphery a helical rib, longitudinal ribs connecting convolutions of the helical ribs, and means arranged to cause the ribs to roughen the surface of the work.

In testimony whereof have signed my name to this specification.

JOHN W. COSGROVE.
